UNITED STATES PATENT OFFICE.

WILLIAM H. BRYANT, OF OAKLAND CITY, INDIANA.

SECTIONAL WAGON-BED.

1,255,290.

Specification of Letters Patent.

Patented Feb. 5, 1918.

Application filed October 26, 1915. Serial No. 58,014.

To all whom it may concern:

Be it known that I, WILLIAM H. BRYANT, a citizen of the United States, residing at 210 W. Cherry St., Oakland City, in the 5 county of Gibson and State of Indiana, have invented certain new and useful Improvements in Sectional Wagon-Beds, of which the following is a specification, reference being had therein to the accompanying 10 drawing.

This invention relates to sectional wagon beds, and has for its principal object the production of a simple and efficient means for 15 adjustably retaining the sides in their correct positions upon the base of the bed when it is desired to have the bed retained in a set-up position.

Another object of this invention is the production of a sectional wagon bed wherein 20 the side portions thereof may be quickly and easily detached from the base of the bed when it is desired to provide a flat bed for any purpose whatever.

Another object of this invention is the 25 production of a simple and efficient brace means engaging the sides of the sectional wagon bed so that when considerable weight is carried within the bed the strain will be relieved from the connecting portions retaining 30 the sides upon the base, and will be taken up by the brace members.

With these and other objects in view this invention consists of certain novel combinations, constructions, and arrangements of 35 parts as will be hereinafter fully described and claimed.

In the accompanying drawings:

Figure 1 is a detailed perspective view 40 of the sectional wagon bed as constructed in accordance with this invention.

Fig. 2 is a side elevation of the sectional wagon bed.

Fig. 3 is a section taken on the line 3—3 of Fig. 2 looking in the directions of the 45 arrows.

Fig. 4 is an elevation of the rear end of the wagon bed.

Fig. 5 is a top plan view of the base of the wagon bed, the sides and front end being 50 removed.

Fig. 6 is a section taken on the line 6—6 of Fig. 4.

Fig. 7 is an enlarged fragmentary sectional view through the forward end of the 55 wagon bed illustrating the manner in which

the sectional forward end is carried upon a certain strip.

Fig. 8 is an enlarged fragmentary sectional view taken upon the line 8—8 of 60 Fig. 4.

Fig. 9 is an enlarged fragmentary sectional view through the forward end of the device, illustrating the manner in which the sectional forward end is held in a set position.

Fig. 10 is a detailed perspective view of 65 one of the retaining brackets used upon the sides of the wagon bed.

Fig. 11 is an enlarged fragmentary sectional view through a portion of the device, 70 illustrating the manner in which the brace members are carried by the retaining clips.

Fig. 12 is a view similar to Fig. 11 illustrating, however, a slightly modified form 75 of a retaining clip.

Referring to the accompanying drawings by numerals it will be seen that the wagon bed comprises a flat base 1 having the bars 2 extending in parallel spaced relation adjacent its central portion and transversely 80 there-across. The bars 3 extend transversely across the lower surface of the base 1 similarly to the bars 2, one of these bars 3 extending adjacent each end of the base 1, as clearly shown in Figs. 1 and 2. An elongated plate 4 is positioned upon the upper surfaces of the bars 2 and 3 and fits beneath the base 1 extending entirely across the base, as clearly shown in Fig. 3. The bolts 5 are passed through the base 1, and also through 90 the plates 4 and bars 2 and 3, so as to carry the nuts 6 upon their lower ends. In this manner it will be seen that the bars and plates will be fixedly and firmly retained in 95 their correct positions upon the lower portions of the base 1. The ends of the plates 4 extend for a short distance beyond the side edges of the base 1 and terminate in the rolled sleeves 7, for purposes to be herein-after set forth.

As will be seen by referring particularly to Fig. 3 the ends of the bars 2 and 3 extend for a considerable distance beyond the side edges of the base 1, and the outer ends of the bars 2 have the notches 8 formed therein, as 105 shown in Fig. 11. A running board 9 is carried upon each side of the base 1 of the wagon body so as to allow the running board to rest within the notches 8 of the bars 2. A clip 10 is positioned upon the outer ends of 110

the bars 2 so as to rest upon the upper surface of the running board 9. A headed rivet 11 is then passed through the clip 10, the running board 9, and bar 2, so as to be permanently retained in position for fixedly connecting these elements together. The outer end of each clip 10 is bent upwardly to provide an upwardly extending lip 12 for purposes to be hereinafter set forth. It will be seen that by the use of the running board 9 a person can stand upon the side portions of the wagon bed for any purpose whatever, such for instance as facilitating the removal or assembling of the side portions of the wagon bed. The outer ends of the bar 3 extend across the base 1 adjacent its rear end and are provided with the clips 10 having the lips 12 formed thereon. It will be noted by referring particularly to Fig. 5 that the sleeves 7 of the elongated plates 4 are carried adjacent one side edge of the bars 2 and 3, so that the clips 10 are carried out of alignment with the plates 4.

Each side 13 may be of any desired height and is elongated so as to be substantially the same length as the base 1. A plurality of retaining brackets 14 are carried upon the outer side surfaces of each side 13 and each retaining bracket comprises an elongated body having a plurality of apertures 15 formed therein, as shown in Fig. 10. The lower end of each bracket is rolled, as shown at 16, so as to fixedly carry a pin 17, while the rolled portion 16 will form an abutment as shown at 18. The retaining brackets 14 are positioned upon the outer side surface of the sides 13, and are retained in position by means of the rivets 19 which pass through the openings 15 and also the sides 13. The brackets 14 are carried upon the sides 13 and will be positioned above the projecting ends of the bars 2 and 3 when the sides are positioned upon the base 1 of the wagon bed, as shown clearly in Fig. 1. It should be noted that the lower ends of the retaining brackets 14 extend for a considerable distance below the lower edges of the sides 13, so that the sleeves 16 and 7 will be carried at a considerable distance below the lower portions of the sides. Therefore, the sides 13 may be positioned upon the base 1 so as to rest upon the base adjacent its side edges, as clearly shown in Fig. 3, at which time the lower ends of the brackets 14 will abut against the side edges of the base 1 for limiting the inward movement of the sides 13 upon the base. At this time the sides 13 will be placed upon the base so as to extend slightly over the rear end thereof, for moving toward the forward end of the base 1. This action will cause the pins 17 to pass into the sleeves 7 formed upon the plates 4, and in this manner it will be seen that the sides will be retained at their lower portions in engagement with the base 1.

The forward movement of the sides will be limited, however, by the sleeves 16 coming into engagement with and abutting against the sleeves 7, as shown clearly in Fig. 1.

In order to retain the sides 13 from swinging outwardly or pivoting upon the pins 17 there are provided a plurality of brace members which comprise body portions 20 and each body 20 is bent inwardly at 21 so as to terminate in the substantially vertically extending end 22 fitting upon the upper portions of one of the brackets 14. One of the rivets 19 used in securing the brackets 14 to the sides 13 also passes through this upper end 22 as well as a second rivet 19'. In this manner it will be seen that the brace members 20 will be fixedly retained in their correct positions and in alignment with the retaining brackets 14. An outwardly extending horizontal foot 23 is formed upon the lower end of each body 20 of each brace, so that when the sides are carried upon the base 1 and the pins 17 are carried within the sleeves 7, the feet 23 of the braces will rest upon the clips 10 so as to allow the outer ends of these feet 23 to abut against the lips 12. It will be seen that by the use of these lips the feet 23 will be held from slipping or springing outwardly from engagement with the clips 10, and, therefore, as these brace members extend upwardly to engage the upper ends of the brackets 14 for supporting the sides 13 at their upper portions it will be seen that these side portions will be positively held from swinging outwardly after being positioned upon the base. When, however, it is desired to remove the sides it will be seen that by pushing upon the forward ends of these sides 13 the pins 17 will be withdrawn from the sleeves 7, while the feet 23 will be moved from engagement with the clips 10, and therefore, the sides may be removed.

After the sides have been positioned upon the base 1, as hereinbefore set forth, it is necessary to retain the same against accidental sliding movement. Accordingly the parallel vertical cleats 24 are positioned in parallel spaced relations upon the forward end and within the inner portions of the sides 13. At this time the front end 25, which is slidably mounted upon the forward ends of the sides 13, is passed downwardly between the parallel spaced cleats 24, as shown clearly in Fig. 1. The brace ribs 26 which are secured upon the forward outer surface of the front or forward ends 25 carry the rod 27 having the depending ends 28 formed thereon. The eyes 29 are passed through a plurality of the cleats 24 and also through the sides 13 so as to carry the nuts 30 for retaining the same in their correct positions. The depending ends 28 are passed through the eyes 29 when the detachable end 25 is positioned between the cleats 24, and

by means of these eyes and the depending ends of the rod 27, it will be seen that the sides 13 will be positively held upon the upper portions of the forward end 25 and will 5 be prevented from spreading. By the use of this rod it will be seen that the brace members are dispensed with at the forward end of the wagon, and thus additional space is provided. Adjacent the opposite end of the 10 side portions of the sides, however, it is impossible to use a rod similar to the rod 27, and therefore, it is necessary at this point to use the brace members. In order to prevent any tendency to rearward movement on 15 the part of the forward end 25 upon the base 1, there is provided a metallic strip 31 which extends transversely across the upper forward portion of the base 1, as clearly shown in Fig. 5, and is retained in position 20 by means of the screws 32. This strip 31 is provided with a vertical flange 33 formed upon its rear edge, and it is upon this strip 31 that the lower portion of the detachable forward end 25 rests. The flange 33 will 25 engage the inner surface of the forward detachable end 25 and therefore, it will be seen that the end 25 will be held against rearward movement. Accordingly it will be seen that the sides 13 will be positively held against 30 rearward movement, while the forward movement of the sides is prevented as hereinbefore set forth by means of the sleeves 16 and 7.

In order to close the rear end of the wagon body there is provided a detachable, although hingedly secured, end gate 34. This end gate 34 is provided with the straps 35 which extend vertically thereon and are retained in position by means of the screws 36 35 which pass therethrough, and into the end gate 34. The lower ends of the straps 35 are provided with the hook portions 37, which engage the U-shaped staples 38 carried by the bar 3, extending across the rear 40 lower portions of the base 1. The guard fingers 39 are carried by the lower portions of the bar 3 and are retained in position 45 by means of the bolts 5 having the nuts 6 which are used in supporting the bar 3. The end 40 of each guard finger 39 extends 50 out of alignment with the body portion of the guard finger so as to be carried at a distance beneath the particular staple 38. When it is desired to retain the end gate 34 55 upon the rear end of the base 1 and in engagement with the rear ends of the sides 13 it is necessary to invert the end gate 34, allowing the same to extend downwardly. The open ends of the hooks 37 may then 60 be passed over the staples 38 so that upon swinging the end gate 34 upwardly the hooks 37 will pass around the staples 38, as shown in Figs. 4 and 8. It will be noted 65 that the projecting end 40 of the guard fingers 39 will fit so as to protect the hooks 37,

preventing their injury when in engagement with the staples 38, and at the same time will constitute a guide for assisting in directing the hooks 37 around the staples 38. The sides 13 are provided with the vertically 70 extending abutment cleats 41, carried at a short distance from their outer end portions so that when the end gate 34 is swung to a vertical plane it will pass between the sides 13 as clearly shown in Fig. 1, so as 75 to abut against the vertical abutment cleats 41. A band 42 is secured upon the sides 13 by means of a rivet 43, and this band extends around the outer portions of the particular abutment cleat 41, and is riveted in engagement therewith as shown at 44. Each band 42, however, projects for a considerable distance beyond the abutment cleats 41 so as to pass through the vertical slots 45 formed in the end gate 34. This end gate 34 is 80 provided with an elongated plate 46 which is retained in engagement therewith by means of the screws 47 and has its end portions provided with the outwardly bent extensions 48 in which there are formed 85 the guide eyes 49, formed in alignment with the openings 50 formed in the projecting ends of the bands 42. A lever 51 having a grip portion 52 is pivotally secured by means of the rivet 53 upon the central portions of the plate 46 and through this lever 51 the retaining rods 54 are pivotally secured. The ends of these rods 54 pass 90 through the guide eyes 49 in each extension 48 of the plate 46 so that when the rods 54 are shifted by means of the lever 51 they 95 will be directed through the openings 50 formed in the bands 42, and, therefore, it will be seen that the end gate will be held from accidentally swinging to an open position. When so desired, however, it is of course obvious that the lever 51 may be 100 swung by the grip portion 52 in a clockwise direction, so as to withdraw the ends of the rods 54 from engagement with the extending portions of the bands 42, thereby 105 allowing the gate 34 to be swung to an open position.

By referring to Fig. 12 it will be seen that a slightly modified form of a clip is provided wherein the clip 10 is provided with a U-shaped outer portion 55 which is adapted to fit around the feet 23 of the braces 20, so that it will be impossible for the feet 23 to swing upwardly or be pried upwardly 110 from engagement with the clip 10 when excessive pressure is brought to bear within the wagon bed.

From the foregoing description it will be seen that a very efficient means has been provided for detachably retaining the side portions and ends of a wagon bed in their correct positions upon the base so as to form a rigid and substantially one-piece wagon bed when so desired. It will further be 115 120 125 130

seen that when so desired the ends of the wagon bed may be quickly and easily removed, at which time the sides may also be removed so as to disengage the base for forming a flat wagon bed for any purpose desired. It should also be noted that by providing the sides with the brace members engaging the clips carried upon the outer ends of the bars and also upon the running board the sides will be efficiently braced so as to prevent their pivoting upon the pins which retain the lower portions thereof in engagement with the base 1.

What is claimed is:

- 15 1. In a device of the class described, the combination of a base, sides positioned upon said base, plates carried upon the lower surface of said base and extending transversely there-across, bars positioned below the lower portions of said base and engaging said plates, bolts passing through said base, plates, and bars for holding the same in fixed engagement with each other, said plates terminating in rolled sleeves at their outer ends, brackets fixedly mounted upon the outer side portions of said sides and terminating in sleeves at their lower portions, pins carried by said last-mentioned sleeves, said pins being adapted to be passed into engagement with said first-mentioned sleeves, whereby said sides will be retained at their lower portions upon said base, and end members demountably carried by the end portions of said base so as to engage said sides, said end members being adapted to hold said sides in a vertical plane and prevent their rearward movement, whereby said sides will be removably retained in their correct positions.
- 20 2. In a device of the class described, the combination of a base, sides positioned upon said base, means for securing said sides to said base, braces fixedly secured upon the outer portions of said side members and extending outwardly toward their lower portions to terminate in horizontally extending elongated flat feet, elongated flat clips having upwardly extending lips formed at their outer ends, means for supporting said clips adjacent said base, said feet rest-

ing upon said clips for bracing said sides, said lips holding said feet from accidentally springing from engagement with said clips, said clips being of broad constructions so as to efficiently support said braces, and said clips permitting said feet to be moved to one side when said sides are removed from said base.

3. In a device of the class described, the combination of a base, sides positioned upon said base, plates carried upon the lower surface of said base and extending transversely there-across, bars positioned below the lower portions of said base and engaging said plates, bolts passing through said base, plates, and bars for holding the same in fixed engagement with each other, retaining means formed upon the ends of said plates, securing means carried by said sides, said securing means engaging said retaining means for holding said sides upon said base, and means for retaining said sides in vertical planes.

4. In a device of the class described, the combination of a base, sides positioned upon said base, plates carried upon the lower surface of said base and extending transversely there-across, bars positioned below the lower portions of said base and engaging said plates, bolts passing through said base, plates, bars, for holding the same in fixed engagement with each other, retaining means formed upon the ends of said plates, securing means carried by said sides and engaging said retaining means for holding said sides upon said base, clips fixedly carried upon said bars, said clips having vertical lips, braces fixedly secured upon the outer portions of said sides and extending outwardly toward their lower portions and terminating in horizontally extending feet, said feet being adapted to rest upon said clips so as to abut against said lips when said side members are positioned upon said base, whereby when said sides are carried upon said base, said sides will be positively retained in vertical positions.

In testimony whereof I hereunto affix my signature.

WILLIAM H. BRYANT.
